(57) **CLAIM**

The ornamental design for an automated machine for a game of chance, as shown and described.

DESCRIPTION

FIG. 1 is a front side perspective view of my new design for an automated machine for a game of chance.

FIG. 2 is a back side perspective view of FIG. 1.

FIG. 3 is a front elevation view of FIG. 1.

FIG. 4 is a back elevation view of FIG. 1.

FIG. 5 is a right side elevation view of FIG. 1.

FIG. 6 is a left side elevation view of FIG. 1.

FIG. 7 is a top plan view of FIG. 1; and,

FIG. 8 is a bottom plan view of FIG. 1.

The features shown in broken lines in the drawing depict disclaimed subject matter only and form no part of the claimed design.

1 Claim, 7 Drawing Sheets
